UNITED STATES PATENT OFFICE.

WILLIAM AITKEN, OF LONDON, ENGLAND, ASSIGNOR TO THE RELAY AUTOMATIC TELEPHONE COMPANY, LIMITED, OF LONDON, ENGLAND.

TELEPHONE SYSTEM.

1,223,020.

Specification of Letters Patent. Patented Apr. 17, 1917.

Application filed February 25, 1916. Serial No. 80,458.

To all whom it may concern:

Be it known that I, WILLIAM AITKEN, a subject of the King of Great Britain, residing at Marconi House, Strand, London, 5 England, have invented new and useful Improvements in Telephone Systems, of which the following is a specification.

The invention relates to line arrangements in automatic and semi-automatic telephone 10 systems, and more particularly to a method of grouping the junctions for the purpose of increasing their traffic carrying efficiency, or for reducing the capacity of the switching apparatus required for establishing the connections.

Owing to the relatively small capacity of the switches used in automatic telephone systems, the subscribers' lines and the junction lines are divided into small groups having 20 access to a particular group only of all the outgoing junctions of the corresponding switching stage. It is known that this grouping of the lines increases the total number of junctions required, and consequently 25 reduces the traffic carrying efficiency of the junctions due to the greater traffic variations in small groups. It is also recognized that the larger the groups of junctions worked in common, the more efficient is the service and 30 the fewer the total number of junctions required to carry the traffic. The maximum number of junctions of each group is, however, as stated above, chiefly determined by the capacity of the switches.

35 It has been proposed to improve the efficiency of the junctions by interconnecting an additional switching stage, thereby giving the incoming lines access to a larger number of outgoing lines without increasing 40 the capacity of the switches. The known double pre-selecting system is an example of this method of increasing the efficiency of the junctions without increasing the capacity of the switches.

45 According to another system the same object is attained without the use of additional switches merely by dividing the multiple of the switches in a suitable manner as described in British Patents No. 22715 of 1914 and No. 20453 of 1914. The arrangement is 50 principally as follows:

A group of outgoing lines of a switching stage is arranged in a number of sub-groups, each accessible to a particular group of incoming lines and adapted to carry only

about the normal outward traffic of the associated group, and in one or more other groups accessible in common to all or a large part of the incoming lines, and adapted to carry the peak loads of all associated groups 60 of incoming lines, the relative number of lines of the various groups being such that the traffic carrying capacity and efficiency of the total of said groups of outgoing lines become practically equal to that of an undivided group serving an equal number of incoming lines. The first mentioned outgoing lines may be called first choice lines and the latter second choice lines, and the arrangement is such that no second choice line 65 is taken into use until the first choice lines of a sub-group are all engaged.

The present invention relates to systems of the kind last mentioned and has for its object further to increase the efficiency of 75 such systems as will be hereinafter described with reference to the accompanying drawings.

Every means for increasing the efficiency of the junctions without increasing the capacity of the switches is evidently also a means for reducing the capacity of the switches without affecting the efficiency of the junctions. This fact is of special importance to automatic systems in which the connections are built 80 up by means of relays only, and in which the switches consequently consist of relays, the economy of such systems being in a higher degree than in other systems dependent on the capacity of the switches. In the following the invention will be described as having for its main object:—to reduce the capacity of the switches, although of course it may be used for any of the said purposes and in any automatic system. The invention can 85 be applied to the pre-selecting as well as to the group-selecting stages, and is not limited to the use of switches of any particular type. 90 In the accompanying drawings

Figure 1 is a diagram illustrating the 100 principal features of the present invention,

Fig. 2 shows the invention as applied to the second pre-selecting stage of a system having primary and secondary pre-selectors,

Fig. 3 shows the invention as applied to 105 group selecting stages, and

Fig. 4 the actual circuits of the switches of a group-selecting stage.

According to the present invention each group G of incoming lines is divided into 110

sub-groups g as shown in Fig. 1, and the first choice groups of outgoing lines are correspondingly divided into first and second choice groups 1C and 2C. 3C represents a 5 third group.

6 The switches are controlled in such a manner that no second choice line is taken into use until the first choice lines available to the calling line are all engaged, and no third 10 choice line is taken into use until all corresponding first and second choice lines are engaged.

15 The grouping should be so carried out that all first and second choice lines may if possible be engaged during the busiest hour of the day.

20 The effect of thus grouping the junctions into first, second and third choice lines is, as can be readily understood, a reduction of the capacity of the switches without affecting 25 the efficiency of the junctions as to their ability to carry the traffic.

The essential feature of the invention will be evident from the following:—

25 If the first and second choice line arrangement is considered as a principal or primary grouping or line scheme, the grouping scheme according to Fig. 1 may be regarded as composed of two primary line schemes 30 united by the third choice lines to a secondary scheme which in its main structure is similar to a primary scheme, but is of a higher order inasmuch as it comprises first, second and third choice line groups. In a 35 similar manner secondary line schemes may be used to form tertiary schemes and so on, whereby the junctions may be divided into first, second, third and fourth choice groups, or any wanted number of groups available 40 in succession. The number of incoming line groups of a primary scheme as well as the number of schemes contained in a scheme of a higher order are of course immaterial to the invention, and may be any number 45 consistent with the traffic requirements. For instance, each primary scheme of Fig. 1 may contain three or more groups g by which the second choice group 2C is used in common, and there may be three or more 50 such primary schemes to which the third choice group 3C is common.

55 In accordance with the sub-division of the outgoing lines, the incoming lines are divided into primary, secondary, tertiary groups, etc., the primary groups g being the incoming line groups of a primary scheme, the secondary groups G the incoming line groups of a secondary scheme, and so on.

60 Fig. 2 shows one form of the invention as applied to the second pre-selecting stage of an automatic telephone system, having primary and secondary pre-selectors. As stated above, the invention chiefly consists only in a particular method of dividing the multiple 65 of the switches whereby the efficiency of the

junctions may be increased without the use of additional switches in accordance with the known double selecting method, but it is apparent that an increased effect is attained by using both methods in combination, as shown in Fig. 2. 70

The figure represents a line arrangement for 1000 subscribers' lines S having access through intermediate lines I to 50 junctions J leading to first selectors. The subscribers' 75 lines are divided into hundred and fifty line groups, S_1, S_2, S_3 , etc., and s_1, s_2 respectively. Each hundred line group S has access to a group i of 10 intermediate junctions I which are divided into 2 first choice groups 80 11C1 and 11C2, including three lines each, and one second choice group 12C comprising four lines, each first choice group being accessible only to 50 subscribers, while the second choice group is accessible to all subscribers of the hundred line group. 85

90 The 50 junctions J are divided into 10 first choice groups 21C1, 21C2, etc., comprising three lines each, two second choice groups 22C1 and 22C2 comprising seven lines each, and one third choice group 23C consisting of six lines. Each first choice group 21C is accessible only to a particular primary group i of intermediate junctions, while each second choice group 22C is accessible to a secondary group II or $I2$ comprising five primary groups i . The third choice group 23C is accessible to all intermediate junctions. The number of lines of the various first, second and third choice 100 groups of the second stage is to be adapted according to the traffic so that during the busiest hour of the day all first and second choice lines may if possible be engaged in all groups. 105

The switches are preferably of the call finder type, so that the subscribers' lines and the intermediate junctions terminate in the multiple of the switches.

110 Fig. 3 shows principally the line arrangement in a group selecting or digit stage. A group of incoming junctions is divided into 12 sub-groups j each having access to two first choice lines 11C and 21C of each numerical group of outgoing lines. In the 115 drawing, only two such numerical groups NG1 and NG2 are shown. Further, two second choice lines, 12C and 22C, are arranged in common to every group of two sub-groups j , three third choice lines 13C and 23C, in common to every group of four sub-groups j , three fourth choice line 14C and 24C in common to every group of six sub-groups j and three fifth choice lines 15C and 25C in common to all sub-groups j . 120 125

The switches may be associated with the incoming junctions, in which case the outgoing lines are connected to the multiple of said switches according to the described division of the same into first, second, third, 130

fourth and fifth choice groups. The operation of the switches is so controlled that a second choice line is not taken into use until the appertaining first choice lines are all engaged, and a third choice line is not taken into use until all first and second choice lines are engaged, and so on.

A circuit diagram illustrating one form of the invention as applied to a group-selecting stage is shown in Fig. 4. The incoming junction P is connected by means of an impulse responder St and a selector Si to outgoing junctions J1, JX. The impulse responder St connects the junction in known manner to the wanted numerical group of outgoing junctions, while the selector Si completes the connection with an idle junction of said group. In the diagram, only two outgoing junctions J1 and JX, belonging to the first numerical group, are shown, whereas the third or test wires TW of all junctions of said first numerical group are represented, and it is to be understood that the line wires LW1 and LW2 are multiplied over the relays of the selector Si in a manner similar to that in which the test wires TW are multiplied. In this case it may be assumed that the outgoing junctions are divided into first, second and third choice groups 11C1, 12C1 and 13C1. J1 is then the first of the first choice junctions, and JX is the last of the third choice junctions.

A subscriber having been connected to the junction P completes a circuit 1 through his telephone instrument and line relay LR and thereafter a circuit 1a is completed over the third wire through relay RR1. The operation of these two relays completes circuit 2 through relay L of the impulse responder St, relay L therefore operates. On the loop circuit 1 being broken for the first impulse, circuits 2a, 2b and 3 are completed, the first being a locking circuit for L, the second an operating circuit for H through a contact of L and the third operating retarded release relay RR2 to prevent closing of circuits 5 and 11. As soon as H operates, it completes circuit 4 to energize relay M. At the termination of the first impulse, LR is again energized and is maintained energized (as in this case only one numerical impulse is being sent) to allow relay RR2 to be deenergized. LR also breaks circuits 2a and 2b and completes circuit 2c, the latter to hold H energized. Due to the breaking of the circuit 2a, L deenergizes, completing circuit 5 through contacts of relays RR2, M and Cr1 and through the coil of relay S, and also completing circuit 6 through cut-off relay CO, which cuts out the line relay and extends the junction P as far as to the open contacts on CR1, H being also energized. S operating completes circuit 7 through control relay C and connects the code wires CW to the coils T, U, V, W, X of the idle line selector Si.

C operating completes circuit 8 through relay E to connect earth to the coding springs 9 and also connects the third or test wires TW of all the junctions of the selected first numerical group to their respective coils AR 70 of the assignor A. If all the junctions are free, none of the assignor relays AR will be energized, consequently circuit 9 will be completed from earth over the back contact of assignor relay AR1, code wire 9, and 75 thence through relay X of selector Si. X will energize, and with the energization of CR1 will connect P to J1. CR1 is at the same time energized through the springs of selector Si to the third wire of junction J1 80 (circuit 10). CR1 operating completes circuit 11 to hold X energized and breaking circuit 5 releases S which deenergizing disconnects the code wires from Si and also releases assignor A by breaking circuit 7. 85

The contacts of the relays AR are so connected that the selector Si is always operated to establish connection with the first idle junction counting from junction J1 to JX. As a consequence the assignor automatically 90 operates according to the invention to fill up all preceding groups before a junction of the subsequent group is taken into use. The invention therefore does not in any way affect the construction of the switches and 95 the circuits. Its main feature, as already stated above, is to be seen in the particular division of the multiple of the switches.

If, for instance, there is only one junction free, and that is junction JX, all the coding 100 relays AR would be energized except AR5 associated with junction JX. Circuit 15 will therefore connect earth over front contacts of AR1 to AR4 and back contacts of AR5 to the coding wires and to all the relays 105 T, U, V, W, X of the selector Si. This will result in P being connected over front contacts of all the relays Si to JX.

If the call had been to a subscriber in the second numerical group, L would be connected by St to P2. This would be effected 110 as follows:—

The loop of P due to a subscriber being connected thereto would operate LR and earth on the third wire would energize RR1. 115 The energization of these two relays would complete circuit 2 to operate L of selector St. At the first impulse, LR would deenergize, completing circuit 3 through RR2 and circuits 2a and 2b, the former being a 120 local circuit to L and the latter operating H. On the loop being again closed, L would be released and circuits 2c and 4 would be formed, 2c being a locking circuit for H and 4 an operating circuit for M. On loop 125 circuit 1 being broken a second time for a second impulse, LR would be again deenergized, breaking circuit 2c allowing H to deenergize. The deenergization of H would complete circuits 13a and 13b, the first to 130

- lock M and the second to energize I. On I energizing, circuit 14 would be formed to energize N over a front contact of I and back contact of J. When LR again energizes at the end of the second impulse, circuit 2 would be formed, energizing L. It will be seen that, due to the energization of I, the calling junction would be connected to P2 and due to the energization of L, M, N, a circuit 18a would be completed to a relay corresponding to S and associated with another selector of idle lines in the second 1000 line section. Circuit 18 would be formed to operate CO.
- 15 It will be seen that during the whole period of a conversation the impulse responder St and the selector Si must be held operated and must be under the control of the calling subscriber connected with P.
- 20 St is retained energized so long as an earth is maintained on the wire EW due to the energization of RR1. This is held energized so long as a subscriber is connected to P by earth on wire 1a. Si is held energized by
- 25 a circuit (11) over contacts on St and a contact on CR1. As soon therefore as the subscriber initiating the call releases P, the impulse responder is free, the relays of which, deenergizing, break holding circuit
- 30 11 of Si, which in its turn releases, disconnecting P from J to which it had been connected.

The invention is applicable to any electro-mechanical system. Thus, in a system using 35 wipers passing over banks of 10 contacts, the first five contacts may be first choice lines and contacts 6 to 10 second choice lines, or if larger groups are required, one level may be utilized for the first choice lines, and the 40 second level for second choice lines, the shaft being stepped up automatically in a known manner to the second choice lines, if all the first choice lines are engaged.

In systems having movement in one direction 45 only, the first 10 contacts may be first choice lines and the second 10 second choice, or the contacts may be otherwise suitably divided.

What I claim is:—

- 50 1. In a telephone system, the combination of a number of groups of incoming lines, each group being divided into a number of sub-groups, a group of first choice outgoing lines associated with each sub-group of incoming lines, means for connecting an incoming line to a first choice line, a number of groups of second choice outgoing lines,

each of such groups being associated with a group of incoming lines, means adapted, when all the first choice lines available to 60 an incoming line are busy, to connect an incoming line to a second choice line, a number of third choice outgoing lines available in common to a number of groups of incoming lines and means adapted, when all 65 the first and second choice lines available to an incoming line are busy, to connect such incoming line to a third choice line.

2. In a telephone system, the combination of a number of groups of lines incoming to 70 a switching unit, each group being divided into a number of sub-groups, a group of first choice lines connecting such unit to a second switching unit and associated with each sub-group of incoming lines, switches adapted to connect an incoming line to a first choice line, a number of groups of second choice lines connecting the first unit to the second switching unit, each of such groups being associated with a group of incoming 75 lines, switches adapted, when all the first choice lines available to an incoming line are busy, to connect an incoming line to a second choice line, a number of third choice lines connecting the first unit to the second switching unit and available in common to a number of groups of incoming lines, switches adapted, when all the first and second choice lines available to an incoming line are busy, to connect such incoming line to a third choice line, such first, second and third choice lines being divided into a number of groups and each group being divided into a number of sub-groups, a group of first choice lines outgoing from the second switching unit, and associated with each sub-group of connecting lines, switches adapted to connect a connecting line to a first choice outgoing line, a number of groups of second choice outgoing lines, each of such groups being associated with a group of connecting lines, switches adapted, when all the first choice outgoing lines available to a connecting line are busy, to connect such connecting line to a second choice outgoing line, a number of third choice outgoing lines available in common to a number of groups of connecting lines and switches adapted, when all the first and second choice outgoing lines available to a connecting line are busy, to 100 connect such connecting line to a third choice outgoing line.

WILLIAM AITKEN.
